GENERATOR FOR GAS-MANTLE LAMPS

Thomas H. Stafford, Meredith, N. H.

Application October 16, 1931, Serial No. 569,175

4 Claims. (Cl. 67—50)

This invention relates to portable lamps, and has particular reference to that type of lamps which generate gas from a liquid fuel such as kerosene and gasoline, and employ mantles which are heated to incandescence by the burning gas. In a heretofore known lamp of this type the fuel is contained in a reservoir or font, and is under pressure which forces it up through a feed tube and into a vaporizing chamber located to receive heat from the incandescent mantle or mantles, so as to gasify the liquid fuel. The vapor then passes through a somewhat tortuous passage to which air is admitted and mixed with the gas vapor, and the mixture then issues from one or 15 more nipples having mantles of a well-known type attached thereto.

Lamps of this type require that occasional access be had to the generator to keep the passageway therethrough free from obstructions. A 20 difficulty has been found to exist in regard to the filter tubes. Such tubes usually have fillings or wicks of asbestos, and after some use the wicks become so filled with carbon that sufficient fuel cannot pass through the tubes which must then 25 be replaced by new wick filled tubes.

All generators for lights of this type past and present, have trouble more or less with the orifice clogging. A cleaning wire to keep the orifice open is furnished with said lights.

An important feature of my invention resides 30 in a structure whereby no obstructions whatever will occur in the generator, this being due to the fact that the tubing is of different sizes and different relative shapes so that the vapor passes through leaving no residue to collect and put the generator out of commission.

Another important feature of my invention resides in a structure which permits access to all inner parts of the generator to facilitate replacement of any part that may be accidentally damaged. It must be understood that my generator is a non-plugging-up device. It is not a device just to produce hydrocarbon vapor gas to burn in mantles, and in a short time have some part fill with carbon so that the operator would have to throw the whole thing away. This generator will last as long as the metal of which it is made, and can be kept in good working order year in and out if run according to directions. A deviation therefrom will not spoil it but may necessitate a little time spent in cleaning.

Other features of my invention, and the advantages thereof, will be explained hereinafter and pointed out in the claims.

Of the accompanying drawing:—

Figure 1 is a front elevation of so much of one of my complete lamps as is necessary to an understanding of the invention, the fuel reservoir or font, and the shade, being omitted as unnecessary to illustrate.

Figure 2 is a side elevation of the same.

Figure 3 represents a vertical section, on an enlarged scale, of those parts which embody my invention.

Similar reference characters indicate similar parts or features in all of the views.

Rising from a suitable base font not shown, is a supply tube 11 for the fuel oil, the upper end of said tube entering a suitable block or bracket 10, 15 in which is mounted the lower end 12 of the tube through which the fuel passes. Said portion 12 is illustrated in Figure 3 as removably containing a wire coil containing fibrous material such as illustrated and claimed in Letters Patent No. 20 1,340,424 issued to me May 18, 1920. Such coil may be included in or omitted from the present structure. If said coil and filling are omitted from the said structure, the enlarged lower end of said fuel supply tube would be eliminated, and 25 said fuel supply tube would have a fuel inlet hole five or six thousandths of an inch in diameter.

Above the portion 12 the tube is somewhat contracted as at 13 to prevent too free passage of fuel through the coiled portion 14. By means 30 of a cup and cone gas tight joint 16, the portion of the fuel supply tube above the coil 14 is connected to the vaporizing tube 18, a suitable connecting nut being illustrated at 17, said nut engaging the threaded lower end of the tube 18 as 35 at 19.

The extended small extreme upper end of fuel supply tube 12 projecting into the elongated inside vacant space in the lower end of the vaporizing tube 18, has a closed end and side perforations, and it being alined in close proximity to the inside wall of said elongated inside vacant space in tube 18 serves as a coarse-misting tube, the purpose or object of which will be explained hereinafter. The upper end of the vaporizing 45 tube 18 is connected as by screw-threads 20, with the lug or top enlargement 25 of the retort 26, or it may be held by friction. The vapor of fuel passes through a port 21 in the enlargement 25 into the retort 26.

Fitting the inside of the vaporizing tube 18 is a vapor regulating screw or spiral 22 having a larger screw-threaded upper end 23 engaging a threaded hole in the enlargement 25, this mounting enabling the said screw to be removed if nec- 50, 55.

essary. Inclosed in the retort 26 is an inner tube 24 having a small hole 27 in one side, and in line with said inner tube 24 is a tube 28 which connects or completes the vapor passage with 5 a suitable air-intake tube 34. The tube 28 has a screw-threaded connection at 29 with the lug or enlargement 25, and its upper end 30 enters the air-tube 34. The lower end of the retort tube 26 is closed by a suitable removable cap 31. 10 The mixed air and fuel vapor pass into a chamber 36 where more complete mixing is effected as is customary in devices of this type, and then through gas tubes 35 to the usual mantles 37.

The general operation of lamps of the type 15 described is so well known that it is unnecessary to herein describe more than the purpose, operation, and advantages of the several features of improvements illustrated.

The small perforated coarse-misting tube 15, 20 extending into the inside vacant space in the vaporizing tube 18 in close proximity to the inside wall of said tube 18, has a three fold purpose; first it feeds the fuel from fuel supply tube 12. It does this by perforations in the side wall of 25 said coarse-misting tube 15, in contact with the boiling and simmering fuel between the hot wall of said coarse-misting tube 15 and the inside hot wall of the vaporizing tube 18. This gives a coarse mist of fuel which is quickly changed to 30 fine fuel vapor. Second, tube 15 is designed to be in close proximity to the inside wall of said vaporizing tube 18, to use the boiling and sim- 35 mering agitation of fuel to break the affinity of the flow of fuel, creating an absorbing process to prevent spattering of fuel away from the hot inside wall of the vaporizing space in the tube 18, thus eliminating a mixture of both poor and good vapor which tends to adhere to the working parts of this device. Third, coarse-misting 40 tube 15 is designed to be in close proximity to the inside wall of said vaporizing tube 18, to eliminate the stoppage of fuel through its fine perforations by the boiling and simmering agi- 45 tation of fuel around said perforations in the vaporizing tube 18.

The elongated inside vacant space in the lower end of vaporizing tube 18 between the retarding screw or spiral 22 and the bottom of tube 18, is designed to give vent to the fuel flashings and 50 compression of vapor caused by the quick change from a coarse mist to a fine vapor of fuel in vaporizing tube 18 when in operation.

The portion 13 of the oil supply tube, which is reduced in size, permits but a small stream 55 of fuel to pass, thereby enabling that which does pass to the coils 14 to be so heated in the coils 14 as to be converted almost, but not quite to vapor in the coils.

The screw or spiral 22 inside of the vaporizing 60 tube 18 is not a vaporizing member. It is a vapor retarding member and is designed solely to retard the pressure of the fuel flashings of vapor made in the inside vacant space in the vaporizing tube 18. This causes a steady stream of 65 vapor to pass through said retarding member and through enlargement 25 into the retort 26. This is accomplished by said retarding member 22 having a small passage-way, and a long passage not being subject to vaporization of fuel. 70 It is understood that the vapor is first made in the inside vacant space in the vaporizing tube 18, before entering the thread in screw or spiral 22.

Retort 26 is not a vaporizing unit. It is an 75 added vapor cleaning unit and is not essential

to vaporization. Retort 26 is designed solely to clean the vapor, to prevent the orifice from getting clogged by dirt which in times past has caused much trouble in all generators of this type of lights. 5

This cleaning process is accomplished first, by the steady stream of vapor passing through enlargement 25 and entering the large port hole 21 to the outside tube of said cleaning retort 26. The vapor strikes the outside wall to inner 10 tube 24 in retort 26, thus retarding the onward pressure of vapor from port 21, and causing the heavy foreign substance in said vapor to settle down at the bottom of retort tube 26. It is understood that preferably I have a very small 15 entrance hole 27 in inner tube 24 which is located below midway of the inside portion of said inside tube 24. This is to buffet the settling foreign substance from entering said small hole 27 in inner tube 24. Second, the dirt now being 20 trapped, the vapor enters the small hole 27 through inner tube 24 and passes through the orifice in the upper end of the outward portion of said inner tube 24, and thus enters the air tube 25 to the gas head.

It is to be understood that although I have described my invention as particularly a generator for kerosene or gasoline lamps, I do not limit myself to lamps, as said generator may be employed for supplying fuel to other devices. 30

Having now described my invention, I claim:

1. In a generator of the character described, a tube for fuel oil, said tube having a cup-shaped upper-end, said cup-shaped upper-end having a coarse-misting tube, one end of which is fastened 35 into said cup-shaped upper-end, the other end of said coarse-misting tube being closed and projecting out of said cup end, said projecting end of said coarse-misting tube being laterally per- 40 forated near its closed end.

2. In a generator of the character described, the combination of a tube for fuel oil, said tube having a cup-shaped upper-end, said cup-shaped upper-end having a small coarse-misting tube one 45 end of which is fastened in said cup end, the other end of said coarse-misting tube being closed and projecting out of said cup end and having side perforations near its closed end; and a vaporizing tube having a cone-shaped lower end, ground to fit said cup-shaped end of the tube for 50 fuel oil, said cone-shaped end of the vaporizing tube having screw-threads adjoining said cone whereby the said coarse-misting tube projects into said vaporizing tube, and a nut fitted to the outer surface of said cup, said nut having inner 55 threads to fit the thread adjoining the cone of the vaporizing tube, to draw said cup and cone together; a removably mounted member in the upper end of said vaporizing tube to receive the flashings of vapor caused by quick vaporization 60 in said inside elongated vacant space in said vaporizing tube, to smooth the vapor by retarding the flow thereof, a vapor cleaning retort coupled to said vaporizing tube and arranged in such a way that when the vapor passes through the 65 entrance to said retort, said vapor strikes a member in said retort which retards the onward pressure of said vapor, thereby causing the heavy part of said vapor to settle down; a buffeting outlet hole in said retort arranged in such a way 70 as to take only the light clean part of said vapor into an outlet tube connected to said retort, said connected outlet tube having the final orifice.

3. In a generator of the character described, comprising a vaporizing tube, a vapor cleaning 75

retort, comprising vertically, concentrically mounted, tubular members, the inner tubular member being perforated intermediate its ends, means closing the lower end of both tubular members, the outer tubular member communicating with said vaporizing tube adjacent to its upper end, and the inner tubular member being adapted to communicate at its upper end with a burner.

5 10 4. In a generator of the character described, the combination of a tube for fuel, said tube having a cup-shaped upper end, said cup-shaped upper end having a small coarse-misting tube, one end of which is fastened into said cup end, 15 the other end being closed and projecting out of

said cup end, and having two squarely drilled coarse-misting outlets on opposite sides of said projecting end; a vaporizing tube having an elongated inside vacant space in its lower end, and a vapor retarding member in its upper end; 5 said fuel supply tube adapted to enter a hole in the lower end of said vaporizing tube in connection when in operation, with boiling and simmering fuel agitation around the outlet holes of said coarse-misting projecting end, said coarse-misting projecting end being aligned in close proximity to the inside wall of said vaporizing tube.
